ATTORNEY

UNITED STATES PATENT OFFICE.

WARREN E. WALKER, OF BLOOMFIELD, NEW JERSEY, ASSIGNEE TO COOPER HEWITT ELECTRIC COMPANY, OF HOBOKEN, NEW JERSEY, A CORPORATION OF NEW JERSEY.

SWITCH MECHANISM.

Original application filed October 1, 1924, Serial No. 741,080. Divided and this application filed March 25, 1927. Serial No. 178,286.

My present invention relates to electric switches of the liquid flow type and particularly to such a switch in which means is provided for moving the switch into the circuit breaking position or into the circuit making position through complete movement from one position to the other without possibility under normal conditions of the switch of stopping the switch at a critical position such as at a position in which sparking might occur in the making or breaking of the circuit.

It is an object of my invention to provide such a switch with simple movement members.

It is also an object of my invention to provide such a switch with compact dimensions, occupying a minimum amount of space, and having simple operating parts. Further objects of my invention will appear from the specification and drawing.

Various objects and advantages of the invention will be obvious from the following particular description of one form of mechanism embodying the invention or from an inspection of the accompanying drawings; and the invention also consists in certain new and useful features of construction and combinations of parts herein-after set forth and claimed.

In the accompanying drawings there is shown for purposes of illustration one form of mechanism embodying the invention, in which

Fig. 1 is an elevation view taken of an embodiment of the invention in which a toggle arrangement is provided for giving positive movement to the switch, and

Fig. 2 is a plan view of the switch of Fig. 1.

In the form of the invention illustrated in the drawing the wall plate 50 carries on the rear side thereof two pivoted bars 51 and 52 one pivoted at a point directly above the other at points 53 and 54 respectively. Said upper bar 51 carries by means of bolts and nuts 28 and 29 and the terminal straps 24 the mercury switch 20. Depending from said bar 50 at a point below its pivot 53 is the bar 55 which terminates at a point near said bar 52 and extends upwardly through said bar 52, at a point

above its pivot 54 is the bar 56, the tension spring 57 connects said bars 55 and 56 at points near their respective outer extremities. The two push buttons 60 and 61 extend through said plate 50 and carry cam surfaces 62 and 63 respectively which engage cam surface 65 on said bar 52. The link 67 is pivoted at its center on the bracket 68 mounted to said wall 50 and at its respective ends to said push buttons 60 and 61 serves to cause the one of said push buttons outwardly when the other is pushed inwardly. The notch 70 in said link 67 is formed to allow movement of said link 67 close to the electrode bolt 71 of said switch 70 and thereby adds to the compactness of structure of the switch mechanism.

In the use and operation of the switch illustrated and starting from the position shown in these figures which is the closed circuit position of the switch to open the switch the push button 61 is pushed inwardly at full length whereupon the cam surface 63 thereof engaging the surface 65 of bar 52 depresses that end of bar 52, the button 60 at this time being retracted through link 67 whereby its cam surface 62 permits that end of bar 51 to rise. Upon such movement the bar 56 is tilted from extreme left to extreme right position whereby said spring 57 is tension and upon the movement of said bar 56 past the vertical medium line said spring 57 will cause the bar 55 to be tilted from extreme left to extreme right position in one positive movement. Upon movement of bar 55 from left to right the switch 20 is tilted from the closed circuit position into the open circuit position. A similar pushing inward of button 60 causes the switch to move with a positive and continuous movement from the open circuit position into the closed circuit position.

While I have shown and described and have pointed out in the annexed claims certain novel features of the invention, it will be understood that various omissions, substitutions and changes in the forms and details of the devices illustrated and in their use and operation may be made by those skilled in the art without departing from the spirit of the invention.

This application is a division of my co-pending application Serial Number 741,080, filed October 1, 1924.

I claim:

- 5 1. In an electric switch mechanism, a liquid flow switch mounted for pivotal movement, a pivoted member having spring toggle connection with said switch, and two push buttons connected to said toggle
- 10 through cam surfaces and adapted to move said switch through said spring toggle in either direction on its support respectively.
- 15 2. In an electric switch mechanism, a liquid flow switch mounted for pivotal movement, a pivoted member having spring toggle connection with said switch, and two push buttons connected to said toggle through cam surfaces and adapted to move said switch through said spring toggle in either direction on its support respectively
- 20 and means connecting said push buttons for pushing the one out when the other is pushed in.
- 25 3. In an electric switch mechanism, a pivoted member, a liquid flow switch connected

to said member for movement thereby, a second pivoted member, toggle connection between said pivoted members, two push buttons having cam surfaces engaging second said member and adapted to move it one in 30 a clockwise and the other in a counterclockwise direction respectively, and means for pushing one of said push buttons out when the other is being pushed in.

4. In an electric switch mechanism, a pivoted member, a liquid flow switch connected to said member for movement thereby, a second pivoted member, spring toggle connection between said pivoted members, two push buttons having cam surfaces engaging second 35 said member and adapted to move it one in a clockwise and the other in a counterclockwise direction respectively, and means for pushing one of said push buttons out when the other is being pushed in.

Signed at Hoboken, in the county of Hudson and State of New Jersey, this 23rd day of March, A. D. 1927.

WARREN R. WALKER.
